UNITED STATES PATENT OFFICE.

WALTER M. ELLIS, OF ENDEAVOR, WISCONSIN.

MECHANISM FOR FLYING MACHINES.

Application filed April 5, 1923. Serial No. 630,175.

To all whom it may concern:

Be it known that I, WALTER M. ELLIS, a citizen of the United States, residing in the city of Endeavor, county of Marquette, and State of Wisconsin, have invented new and useful Improvements in Mechanisms for Flying Machines, of which the following is a specification, reference being had to the accompanying drawings.

10 This invention is in the nature of an air ship mechanism, or mechanism for heavier-than-air flying machines, and the object is to provide a combination mechanism, system, means and method for accomplishing and 15 carrying out all the activities and functions of air navigation by means of a mechanism consisting essentially of two distinct parts, namely, an overhead frame with a system or plurality of coacting propellers, helicop- 20 ters or wheel-wings; connected below, by means of a universal joint, with a body or carriage part; and means for rotating propellers or wheel-wings in unison; and separate means for flexing or inclining the wheel- 25 wing system and frame in any desired direction or angle to the vertical, in order to direct the course or travel of the air ship.

In the drawing

Figure 1 is a side elevation of a representation or embodiment of the invention 30 designed to accomplish the objects stated. (A mid-section of the air ship is here shown.)

Figure 2 is a plan view of the propeller 35 or wheel-wing frame, in essential and conventional, but not detailed, showing.

Figure 3 is in outline a side view of the 40 universal joints, the articulating or supporting part enclosing the part connecting the sections of the driving shaft.

Figure 4 is a plan view of the double universal connections.

In developing and carrying out this invention, a propeller or wheel-wing frame 1 is provided and rigidly braced as a whole; and through the borders of this frame are journaled two or more pairs of propeller or wheel-wing shafts 2, carrying wheel-wings or propellers 3, all set in a common plane. 45 A central transmission shaft 4 is likewise journaled through the center of the frame, and rigidly mounted thereon are a number of sprockets 5, corresponding in number to the number of propellers used (four as here 55 represented). Two brackets 6 depend from the longitudinal axis of the frame 1, and

two similar brackets 7 are extended up from the transverse axis of the air ship 8. A ring 9, having four pintles 10 equi-spaced ninety degrees apart around the outer edge thereof, is journaled by two opposite pintles between the ends of the frame brackets 6, and by the other two opposite pintles between the ends of the body brackets 7; thus a universal supporting joint or connection 60 11 having an open center 12 is formed between the frame 1 and the ship 8. By means of another, smaller and more conventional form of universal joint 13, located within the open center 12 of the supporting joint 11, and which for convenience may be referred to as a driving connection, the lower extended end of the shaft 4 is flexibly joined to the vertically journaled drive shaft 14. The drive shaft 14 is operatively connected 70 with the engine shaft 15 by means of bevel gears 16, or other conventional connection. The points or centers of flexure of the two joints 11 and 13 are of course located in the same horizontal plane. Guy ropes or cables 80 17 are attached to the mid-sides of the lower part of the frame 1 and pass into the body of the ship over rollers 18. By manipulating these ropes the engine can control and flex the frame and wheel-wing system in 85 any direction and so direct the movement of the air ship.

While I have herein described a certain specific manner and method of constructing and assembling the elements of my invention, it is understood that I may vary from the same in minor details, not departing from the spirit and essential conception of my invention so as to best construct a practical device for the purpose intended, as defined in the appended claims.

I claim:

1. A mechanism of the character described comprising in combination with the body, engine and essential parts of a flying machine, a propeller or wheel-wing frame adapted for horizontal disposition over the said body, a central transmission shaft and a plurality of outer propeller or wheel wing shafts journaled through the frame perpendicular thereto and operatively connected together, propellers or wheel wings mounted on the outer shafts in a common plane, a vertical drive shaft centrally journaled in the body in line with the transmission shaft and operatively connected 100 with the engine, a universal joint centrally 105 with the longitudinal axis of the frame, and rigidly mounted thereon are a number of sprockets 5, corresponding in number to the number of propellers used (four as here 110 represented). Two brackets 6 depend from the longitudinal axis of the frame 1, and

connecting the wheel wing from above with the body below, one part or element of said universal joint consisting of a ring provided with radial pivots arranged in the same plane and having an open center, and operated to articulate and mutually support the two parts of the airship, the other part or element being located exactly centered and actuating within the outer part and at the same point of flexure as the outer or articulating point and operatively connecting the drive shaft with the transmission shaft, and guy ropes attached to the outer lower part of the wheel wing frame and extending thence into the body to a central point of control for flexing the wheel wing system or frame at the will of the driver and thus directing the movement of the airship.

2. A mechanism of the character described comprising in combination with the body, an engine of a flying machine, a drive shaft journaled in the body and operatively connected to the engine, a transmission shaft vertically connected at the upper end of the drive shaft through a universal joint, a perpendicular frame, the latter being journaled to the former, perpendicular shafts vertically journaled one through each corner of the perpendicular frame, sprockets on the transmission shaft, aligned sprockets on the perpendicular shafts, sprocket chains connecting the said aligned sprockets, propellers mounted on the upper ends of the propeller shafts, and front and rear guy ropes arranged in pairs and attached at their upper ends to the corners of the propeller frame and extending downwardly directly to the body at opposite sides of the same for controlling the propeller frame to tilt the same laterally or longitudinally.

3. A mechanism of the character described, comprising in combination with the body, an engine of a flying machine, a propeller frame adapted for horizontal disposition over the said body, a central transmission shaft, a plurality of outer propeller shafts journaled through the frame perpendicular thereto, propellers on the propeller shafts, means for operatively connecting the transmission shaft with the propeller shafts, a drive shaft vertically journaled in

the body and operatively connected with the engine, a universal connection between the drive shaft and the transmission shaft, front and rear guy ropes arranged in pairs and connected at their upper ends to the corners of the propeller frame and extending downwardly directly therefrom to the body for adjusting the propeller frame to tilt the same laterally or longitudinally.

4. A flying machine comprising a body portion, a drive shaft vertically and centrally journaled in the body portion, means for rotating the drive shaft, a helicopter portion disposed above the body portion, a transmission shaft vertically and centrally journaled in the helicopter portion, a central universal supporting connection between the body and the helicopter portion, said connection having a ring provided with a central opening and having four radially arranged pivots located in the same plane and extending outwardly from the periphery of the ring, two of the pivots connecting the ring with the body portion and the other two of the pivots connecting the ring with the helicopter portion and a central universal driving connection between the drive shaft and the transmission shaft, said driving connection being arranged within the central opening of the said ring.

5. A flying machine comprising a body portion, a drive shaft vertically and centrally journaled in the body portion, means for rotating the drive shaft, a helicopter portion disposed above the body portion, a transmission shaft vertically and centrally journaled in the helicopter portion and operatively connected therewith, and a central universal supporting connection between the body portion and the helicopter portion comprising a ring provided with radial pivots located in the same plane, and brackets arranged in pairs and mounted on the body portion and the helicopter portion and having bearings receiving the said radial pivots, and a universal driving connection located within the ring and connecting the vertical shafts.

WALTER M. ELLIS.
